LOUIS B. HASBROUCK, OF ELMIRA, NEW YORK, ASSIGNOR TO ECLIPSE TEXTILE DEVICES, INC., OF ELMIRA, NEW YORK, A CORPORATION OF NEW YORK

YARN CLEANER

Application filed January 12, 1928. Serial No. 246,130.

This invention relates to yarn cleaners for removing impurities from traveling yarns and aims to provide a simple and effective device for detaching specks and other particles from a traveling yarn and continuously discharging and collecting such impurities.

The invention relates particularly to the type of yarn cleaner, invented by me, in which the traveling yarn is drawn between a plurality of scraping edges and the smooth surface opposite to these edges. The invention involves improvements in the yarn cleaners of this type shown in U. S. Patents Nos. 1,565,850, 1,565,851, 1,565,852, all issued on December 15, 1925. The improvements effected by the present invention include facilitating the discharging of the impurities by inclining the smooth surface and the scraping edges away from each other below the yarn, providing a collector for the impurities, and providing an improved form of scraping blade. This and other features of the invention may best be understood from a detailed description of the specific yarn cleaner embodying the invention which is shown in the accompanying drawings in which:

Fig. 1 is a side elevation of the cleaner;

Fig. 2 is a plan view of the cleaner;

Fig. 3, on a larger scale than Figs. 1 and 2, is a longitudinal section of the cleaner, taken on the line of travel of the yarn, looking toward the scraping edges;

Fig. 4 is a plan view on the same scale as Fig. 3, showing the cover and other parts cut away;

Fig. 5 is a longitudinal section taken on the same plane as Fig. 3, but looking in the opposite direction and showing the smooth surface opposite the scraping edges;

Fig. 6 is an enlarged transverse section of the cleaner on the line 6—6 of Fig. 4, omitting the pins for supporting the yarn;

Fig. 7 is a front view of one of the scraping blades on a still larger scale;

Fig. 8 is an end view of one of the scraping blades, looking in the same direction as in Fig. 3, and

Fig. 9 is a section of one of the cleaning blades taken on the lines 9—9 of Fig. 7 and Fig. 8, and on a still larger scale.

The yarn cleaner illustrated is intended to operate upon a traveling yarn which is being drawn from the bobbin or cone into a winding, spooling, or other machine. The cleaner may conveniently be secured to the portion of the frame of any such machine, and for this purpose there may be secured to the frame 10 of the cleaner, a bracket 11 mounted on a bar 12 secured to, or forming a part of, the machine with which the cleaner is to be used. 55 It will be understood, however, that the cleaner may be mounted in any desired manner, and will operate on any traveling yarn, regardless of the nature of the machine in which the yarn is being drawn.

The frame 10 of the cleaner is rectangular, and the ends 13 and 14 of the frame, may conveniently be integral with the one side 15 of the frame. To provide for adjustment, as hereinafter explained, the other side 16 of the frame is slidably mounted, by means of recesses 17 in its ends, on studs 18 projecting from the ends 13, 14 of the frame. The side 16 is attached to the ends 13, 14 by means of screws 19, which pass through outwardly projecting brackets 20 secured to the side 16, and are threaded in the ends 13, 14. Compression springs 21 surrounding these screws, and reacting between the ends of the studs 18 and the brackets 20 hold the side 22 firmly in fixed relation to the heads 22 of the screws 19. These springs also prevent turning of the screws under any vibration to which the device may be subjected. It is apparent that the distance between the 75 two sides of the frame may be nicely adjusted by turning the screws 19.

The side 16 of the frame is set at a sufficient distance from the end pieces 13 and 14 of the frame, to provide recesses 23 above the inner portions of the studs 18, through which a yarn A may be drawn longitudinally across the frame in contact with the smooth inner surface of the side 16.

Scraping elements 30 are mounted on the 85 side 15 of the frame. Since the arrangement of the scraping elements is dependent upon the direction in which the yarn is drawn through the cleaner, I shall use the word "front" to define the surfaces of the scraping 100

elements which face toward the front end 13 of the cleaner, from which the yarn is intended to enter the cleaner. Each scraping element 30 consists of a single piece of sheet metal providing a supporting bar 31 and a blade 32 which includes a rearwardly inclined supporting part 33 and a forwardly bent operative part 34. One end of the supporting bar 31 is set in a transverse slot 35 in the fixed side 15 of the frame. It is held in this slot by means of the washer 36, which is forced down by screw 37. The supporting bar 31 extends perpendicularly from the side 15 of the frame; the supporting part 33 of the blade 32 extends downward from the lower edge of the end part of the supporting bar, and is bent rearwardly so that this part of the blade is rearwardly inclined, but is perpendicular to the sides of the cleaner; and the operative part 34 of the blade extends outwardly from the outer edge of the supporting part 33 and is bent forwardly, so that while this part of the blade is rearwardly inclined from the vertical like the supporting part of the blade, it is oblique of the line travel of the yarn A, and has its front surface 38 at an obtuse angle to the yarn. The outer edge 39 of the operative part 34 of the blade, which I term the operative edge of the blade, lies in a vertical plane. To increase the scraping action of the blade, its operative edge 39 is provided with a semi-elliptical notch 40 extending parallel to the sides of the cleaner. The surface of the notch 40 and the front surface 38 of the operative portion 34 of the blade intersect in an acute edge 41, which is the scraping edge of the blade. For convenience in threading, the upper corner 42 of the operative portion 34 of the blade is rounded off as shown.

The scraping elements are arranged in the cleaner with their operative edges 39 in a common vertical plane, parallel to the sides 45 of the cleaner and with their notches 40 aligned and just above the upper surfaces of the studs 18.

The smooth inner surfaces of the side 16 of the frame has a flat vertical portion 25 which is directly opposite the notches 40 of the blades, and flat portions 26, 27 above and below the portion 25 and inclined slightly away from the plane of the edges 39 of the blades. The outward inclination of the upper portion 26 facilitates drawing the yarn down into the notches in threading the cleaner, while the outward inclination of the lower portion 27 facilitates discharging of the matter removed from the yarn as hereinabove explained.

A plurality of pins 45 extend inwardly from the side 16 of the frame, with their upper surfaces in the same horizontal plane as the upper surfaces of the studs 18, to prevent the yarn from dropping below the

notches 40 and the vertical portion 25 of the surface 24 when the cleaner is threaded.

A box 50, is provided to collect the impurities removed from the yarn. The box is secured around the frame of the cleaner. The top of the box is open, except for a flange 51, which provides a cover for the cleaner. The edge of this cover 51 has inclined portion 52, which co-operates with a guide 53 on the side 16 of the frame, in directing the yarn into operative position in the cleaner. The front and rear ends 54, 55 of the box 50 are both inclined rearwardly, but for different purposes as hereinabove explained. To facilitate removing the material collected in the box, the back and bottom of the box are preferably made as a continuously curved wall 56.

The cleaner is provided with the usual auxiliary devices—a tension device 57 mounted on a bracket 58 secured to the front 13 of the frame 10, and a slub catcher 59 mounted behind the rear end 14 in the frame.

The use and operation of the cleaner described are as follows: To secure the best operation of the device, the position of the side 16 is adjusted by turning the screws 19 to make the distance between the inner ends of the notches 40 and the flat surface 25 slightly less than the diameter of the yarn to be cleaned, so that both the scraping edges 41 and the flat surface may be in firm contact with the yarn.

The cleaner is threaded by passing the yarn under the tension device 57 and dropping it into the space provided between the inclined portion 52 of the cover 51 and the side 16 of the frame. It is drawn down, being guided by the curved corners 42 of the operative portions 34 of the blades and by the inclined surface 26, until it strikes the pins 45 and is thus positioned between the notches 40 and the vertical surface 25.

In the operation of the device, the yarn is drawn in the direction of the arrow in Fig. 4. When, as is usually the case, the yarn is drawn to the tension device from a cone or bobbin located directly below it, the yarn tends to balloon out below the tension device, as indicated by dot and dash lines in Fig. 1. The rearward inclination of the front wall 54 of the box 50 permits such ballooning, and thus allows free travel of the yarn to the tension device and the cleaner. As the yarn travels through the cleaner, the specks or other impurities which it contains and a slight amount of fibrous matter are scraped from it by the scraping edges 41. The contact of the flat surface 25 with the yarn prevents the fibrous matter from entwining about the yarn. Consequently the particles which are, of course, moving rapidly in the same direction as the yarn when they are scraped off, are directed downwardly and rearwardly between the lower portions of the blades and the inclined surface 27. The fact that this

space increases in width towards its bottom permits the particles to fall freely. The forward motion of the particles is such that a considerable part of them strikes the back 5 wall 55 of the box 50. The inclination of this wall throws such particles downward, so that all the particles and fibrous matter tend to collect at the bottom of the box, where they are well out of the way of the yarn. The matter which collects in the box is periodically removed by passing the hand through the open top of the box and drawing the collected matter outwardly along the curved bottom of the box.

15 In the cleaner which is illustrated in the drawings, the supporting bars 31 of the blades are resilient so that the blades are set into vibration by the travel of the yarn. This increases their cleaning action by giving 20 their scraping edges 41 a brushing action as well as a scraping action on the yarn.

What I claim is:

1. A yarn cleaner for removing particles from a traveling yarn, comprising a plurality of transverse blades having aligned edges adjacent to one side of the yarn, and a member providing a smooth surface opposite said edges at the other side of the yarn, the blade edges and smooth surface being parallel in 25 the immediate vicinity of the line of travel of the yarn and diverging in straight lines at an acute angle as they extend away from said line of travel.

2. A yarn cleaner for removing particles 35 from a traveling yarn, comprising a plurality of transverse blades having aligned edges containing aligned notches, and a member providing a smooth surface opposite the blade edges, the blade edges and the smooth 40 surface being parallel in the immediate vicinity of the line of the notches and diverging in straight lines at an acute angle as they extend away from the line of the notches.

3. A yarn cleaner for removing impurities 45 from a traveling yarn, comprising a plurality of transverse blades having edges lying in a common vertical plane at one side of the yarn, and a member at the other side of the yarn having, in the immediate vicinity of the 50 line of travel of the yarn, a flat vertical surface and, below the line of travel of the yarn, a flat surface inclined away from the plane of the blade edges at an acute angle.

4. A yarn cleaner for removing impurities 55 from a traveling yarn, comprising a plurality of transverse blades having edges lying in a common vertical plane and containing aligned notches, and a member opposite the blade edges having, at the level of the notches, 60 a flat vertical surface and, above and below the line of notches, flat surfaces inclined away from the common plane of the blade edges at acute angles.

5. A yarn cleaner for removing particles 65 from a traveling yarn, comprising a mem-

ber providing a flat vertical surface along which the yarn is drawn, and a plurality of transverse blades having operative edges lying in a common vertical plane parallel to said vertical surface, such blades being so 70 inclined that the lower ends of their operative edges lie behind the upper ends of their operative edges and their front surfaces make an obtuse angle with said flat surface.

6. A yarn cleaner for removing impurities 75 from a traveling yarn, comprising a plurality of cleaning blades having edges lying in a common plane and containing aligned notches extending obliquely across their cleaning edges, said blades having their front 80 surfaces at an obtuse angle to the common plane of their edges, so that their front surfaces intersect the surfaces of the notches to provide acute scraping edges.

7. In a yarn cleaner, a frame, a plurality 85 of supporting bars extending inward from one side of the frame, rearwardly inclined blades extending downwardly from the outer parts of the supporting bars, and having forwardly bent operative portions extending 90 from their outer edges.

8. A yarn cleaner for removing impurities from a traveling yarn, comprising a transverse blade having an operative edge at one side of the yarn and so inclined that the lower 95 end of said edge lies behind the upper end of said edge, a member at the opposite side of the yarn opposed to the operative edge of said blade, said member and said edge being closely adjacent at the line of travel of the 100 yarn and gradually diverging from each other below the line of travel of the yarn.

9. A yarn cleaner for removing impurities from a traveling yarn, comprising a transverse blade having an operative edge at one side of the yarn and so inclined that the lower 105 end of said edge lies behind the upper end of said edge, a member at the opposite side of the yarn opposed to the operative edge of said blade, said member and said edge being closely adjacent at the line of travel of the 110 yarn and gradually diverging from each other below the line of travel of the yarn, and said edge containing a notch at the point at which it is closest to said member.

In testimony whereof I have hereunto set my hand.

LOUIS B. HASBROUCK.
